ATTORNEYS.

UNITED STATES PATENT OFFICE.

FRANK H. LA PIERRE, OF EAST ORANGE, NEW JERSEY.

DESIGN FOR A HAND-GLASS.

SPECIFICATION forming part of Design No. 28,684, dated May 24, 1898.

Application filed April 21, 1898. Serial No. 678,398. Term of patent 7 years.

To all whom it may concern:

Be it known that I, FRANK H. LA PIERRE, a citizen of the United States, residing at East Orange, in the county of Essex and State of New Jersey, have invented and produced a new and original Design for a Hand-Glass; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 is a plan of a hand-glass of my new design; and Fig. 2 is a sectional view of the same, taken at line *x*.

As shown in the drawings, the leading or material feature of my newly-designed hand-glass consists in the "polka-dot" ornamentation displayed on the plain ground at the back of the hand-glass body.

In said drawings, *a* indicates the hand-glass

body, which is round or discous in plan, with a handle at one side, which is outlined by 25 concavous lines *b b* and convex lines *c c*, the latter meeting at the extremity of the handle *d*. The back faces of the body and handle are centrally plain and at the edges are convexly rounded, as at *e*, and the plain central surfaces of the body and handle are ornamented by polka-dots *f*, disposed at wide intervals apart.

At about the center of the wider part of the handle is displayed a polka-dot *g* of larger dimensions than the dots *f*.

30 What I claim as new is—

The design for a hand-glass as herein shown and described.

In testimony that I claim the foregoing I have hereunto set my hand this 18th day of March, 1898.

FRANK H. LA PIERRE.
